UNITED STATES PATENT OFFICE

171,552

TEXTILE FABRIC

John J. Petroske, Methuen, Mass., assignor to
Patchogue-Plymouth Mills Corporation, New
York, N. Y., a corporation of New York

Application September 8, 1953, Serial No. 26,745

Term of patent 14 years

(Cl. D92—1)

To all whom it may concern:

Be it known, that I, John J. Petroske, a citizen of the United States of America, residing at Methuen, in the county of Essex and State of Massachusetts, have invented a new, original, and ornamental Design for a Textile Fabric, of which the following is a specification, reference being had to the accompanying drawing, forming part thereof, wherein:

The figure is a plan view of a textile fabric showing my new design.

I claim:

The ornamental design for a textile fabric, as shown.

JOHN J. PETROSKE.
